UNITED STATES PATENT OFFICE

FRANK H. KNEELAND, OF CHICAGO, ILLINOIS, ASSIGNOR TO SAFETY MINING COMPANY,
OF CHICAGO, ILLINOIS, A CORPORATION

BLASTING CARTRIDGE

Application filed November 25, 1929. Serial No. 409,638.

The present invention relates to blasting cartridges of that type wherein a compressed gas, such as carbon dioxide, is employed as the blasting medium and the blasting pressure of the charge of compressed gas is brought about by applying heat thereto. Heretofore the required heat has been produced by a combustible mixture of chemicals initiated by an electric squib, matchhead or the like. It now appears to be desirable to produce this heat without the aid of combustion.

It is an object of the invention to provide a heating device for blasting cartridges of the type indicated whereby the necessary heat may be produced without the aid of combustion.

More particularly, it is an object of the invention to provide a heating device embodying a plurality of substances which, when combined, are capable of producing heat, with means for bringing the substances together at will.

Another object of the invention is to provide a heating device embodying a plurality of separated substances, with means susceptible of remote control for causing such substances to be brought together.

Other objects and advantages will appear in connection with the following description of the invention as illustrated in the accompanying drawings:

Referring to the drawings,

Figure 1 is a view in longitudinal section of a blasting cartridge of the type with which the present invention may be employed, and illustrating the heater unit in position therein.

Figure 2 is a view in transverse section taken along line 2-2 of Figure 1.

Figure 3 is a view in transverse section taken along line 3-3 of Figure 1.

Figure 4 is a view in transverse section taken along line 4-4 of Figure 1.

Figure 5 is a longitudinal section thru a heater unit constructed in accordance with my invention.

Figure 6 is a view in longitudinal section of the inner container of the heater unit shown in Figure 5.

Figure 7 is a sectional view of one of the metallic end caps for the inner container.

Figure 8 is a detail view of the device for rendering the heater unit active.

Figure 9 is a transverse section along line 9-9 of Figure 5.

It is to be understood that the structure of the cartridge with which the present invention is associated may take a variety of forms and that the particular form herein shown is for the purpose of illustrating the application of the invention.

The structure illustrated in the drawings comprises a metallic body 1 having an open ended internal gas chamber 2 and a rupturable disc 3 arranged to overlie and seal the open end of the chamber. The disc is held in place by a shear ring 4 and a discharge cap 5. It will be noted that in the form shown the discharge cap is substantially spherical and that it is provided with a plurality of radial ports 6 through which gas may be discharged. The opposite end of the cartridge is provided with an electrode 7 and a charging valve 8. The reduced portion 10 of the electrode extends into the gas chamber 2 and is surrounded by an electrode nut 9 which has threaded engagement with the body of the cartridge. Interposed between the outer face of the electrode nut 9 and the enlarged intermediate portion 12 of the electrode, there is provided an insulating and sealing disc 13. This sealing disc may be formed with an axial tubular extension surrounding the reduced portion 10 of the electrode and separating the latter electrically with respect to the electrode nut 9. The opposite end of the electrode is surrounded by a second nut 15 which is screw threaded into the end of the cartridge body and engages an insulating disc 16 which is positioned in engagement with the outer radial face of the enlarged portion 12 of the electrode. The extreme outer end of the electrode is formed to receive a snap-on contact plug as indicated at 11. Surrounding the peripheral portion of the enlargement 12 of the electrode is an annular insulating band 14 which completes the insulation of the electrode from the body of the cartridge. Leading into the gas cham-

ber 2 is a charging passage 16 with which the conical end of the valve 8 is designed to co-operate. When the valve 8 is withdrawn from engagement with the end of the passage 16, this passage is in communication with the principal charging orifice 17 which is designed to cooperate with a suitable charging nozzle. The valve 8 has threaded engagement with the body of the cartridge as indicated at 18 in order to provide for the necessary range of adjustment thereof. A suitable packing 19 surrounds the stem of the valve in order to prevent leakage of gas thereabout. The electrode and valve assemblies are protected by means of a cap 20 which has a screw thread connection with the end of the cartridge body. This cap is provided with a central opening 21 through which a contact plug may be inserted and one or more openings 22 to facilitate the connection of a second conductor to the body of the cartridge. It will be noted that in the cartridge as above described there is provided a circuit including the electrode and the body of the cartridge 25 as terminals and between which an electrically energizable heater unit may be positioned. Such a unit is indicated at 23 in Figure 1 and as therein shown is provided with contacts at its opposite ends, which engage the end of the electrode and the rupturable disc 3 respectively. Heretofore it has been customary to employ heater units consisting of chemicals capable of producing high degrees of heat when ignited by means 35 of an electric matchhead embedded therein and having leads connected to the respective contacts at opposite ends of the heater unit. The heat thus generated is imparted to a charge of gas contained within the chamber 2 40 for the purpose of increasing the pressure of the charge to such a point that the rupturable disc will be blown out.

According to the present invention, there is provided a heater unit designed for use in the manner above described, but wherein the heat required to bring about the blasting pressure of the gaseous charge is developed without the aid of combustion.

Referring particularly to Figures 5 to 9 inclusive, there is shown a heater unit which consists of two concentric tubes 22 and 23, the ends of which are closed by means of metallic caps 25. The ends of the tube 22 are turned inwardly to engage the radial portion of the caps 25 and prevent endwise removal of the caps. The tube 23 is so designed as to snugly fit the interior of caps 25. The space between tubes 22 and 23 is preferably filled with quick lime, while the interior 60 of tube 23 is designed to hold a quantity of water. In order to further seal the ends of tube 23 there is provided a plug 28 and 29 for each end. Thus there is provided a heater, the constituents of which are inert 65 until brought together and for this purpose

there is provided an electric matchhead 30 having leads extending toward opposite ends of the heater unit and connected to metallic caps 25. There is also provided, if necessary, a small container 31 associated with the matchhead and wherein may be provided a very small charge of explosive such as black powder or fulminate of mercury. The tube 23 containing the water is designed to be ruptured by the discharge of the matchhead and the explosive, thus causing a rapid and intimate mixture of the water and the quick lime. The result of this mixture is a relatively rapid production of heat which serves to increase the pressure of the gaseous charge and thereby develop the blasting pressure necessary to rupture the disc.

It will be noted that in the use of the improved heater hereinabove described, the ignition of the matchhead and the explosive will be extinguished substantially coincident with the mixture of the water and quick lime. It will be appreciated, therefore, that the ignition is extinguished before the development of heat is started and that it is therefore impossible for any flame or spark to be present when the discharge of the cartridge takes place. The entire heat required for the discharge of the cartridge is generated by the mixture of quick lime and water, and after the matchhead and small amount of explosive has been extinguished. The only function of the matchhead and explosive is to bring about the mixture of the quick lime and water at the desired time and by a means susceptible of remote control. It is therefore absolutely impossible to cause ignition of mine gases or other explosives by the use of blasting cartridges employing the improved heater herein described.

I claim:

1. The combination with a substantially indestructible blasting cartridge having a gas chamber adapted to be charged with compressed gas, and a pressure responsive venting device adapted to permit discharge of said gas when the pressure of the same has been increased to a substantially predetermined point, of a non-combustible means for causing the said predetermined increase of pressure by the application of heat to the compressed gas.

2. The combination with a substantially indestructible blasting cartridge having a gas chamber adapted to be charged with compressed gas, and a pressure responsive venting device adapted to permit discharge of said gas when the pressure of the same has been increased to a substantially predetermined point, of a heater unit capable of producing heat in sufficient amount to increase the pressure of said gas, by expansion, to said predetermined point, said unit consisting of normally separated substances adapted to be brought together at will and

adapted when so brought together to produce the desired heat.

3. The combination with a substantially indestructible blasting cartridge having a gas chamber adapted to be charged with compressed gas, and a pressure responsive venting device adapted to permit discharge of said gas when the pressure of the same has been increased to a substantially predetermined point, of a heater unit capable of producing heat in sufficient amount to increase the pressure of said gas, by expansion, to said predetermined point, said unit consisting of normally separated quantities of quick lime and water, and means for bringing said lime and water together at will, whereby to produce the desired heat.

Signed at Chicago, Illinois this 19th day of November, 1929.

FRANK H. KNEELAND.
